UNITED STATES PATENT OFFICE.

HENRY E. RICHMOND, OF NORTH BENNINGTON, VERMONT, ASSIGNOR TO ELMER UNDERWOOD AND BERT ELIAS UNDERWOOD, OF SUMMIT, NEW JERSEY.

DESIGN FOR A STEREOSCOPIC-PICTURE HOLDER.

SPECIFICATION forming part of Design No. 33,060, dated August 14, 1900.

Application filed May 26, 1900. Serial No. 18,159. Term of patent 14 years.

To all whom it may concern:

Be it known that I, HENRY E. RICHMOND, a citizen of the United States, residing at North Bennington, in the county of Bennington and 5 State of Vermont, have invented or produced a new and original Design for a Stereoscopic-Picture Holder, of which the following is a specification.

This design relates to a stereoscopic-picture holder of the character used for holding or supporting a picture in a hand-stereoscope.

My design has reference to the shape or configuration of such a picture-holder.

The design is shown in the accompanying 15 drawing, which is a perspective view of a holder embodying my new design.

Referring to the drawing, let A indicate the body portion, B one end, and C the other end, of the holder.

According to the distinctive features of the present design the portion A is an elongated body having approximately-parallel sides a and being substantially flat, except at its middle, where it has a raised portion b, which 20 is of the same width as the main portion of the body A, and at each end of the portion b is a portion c, which curves downwardly from the portion b, and on each side of the curves c are curved portions c', which extend downwardly in compound curves and merge into the main portion of the body. Beneath the middle portion b is a portion d, which extends substantially parallel to the portion b and in approximately the same plane as the main 25 portion of the body A. At the middle of the portion d is an angular depending portion f, which on one side has a shoulder g, the upper face of which extends in a plane approximately at right angles to the direction of 30 tension of the portion f. The portion d is curved upwardly at its ends at h, so that it

merges into the curve c. On each side of the portions b and d is a recess i, which recesses extend from the curved portion c outwardly to nearly the ends of the body A. On the upper face of the body A, at each side, is a bead j, which extends the entire length of the body, being continued at k upon the middle portion b and curves c' at each end thereof. 45

The end B extends upwardly approximately 50 at right angles to the body portion A and near its lower end is divided by a recess l into two upwardly-extending and slightly-converging portions m, which are joined at their upper ends by a curved portion n, and two 55 angular portions o, which extend outwardly from the end portions B and are substantially parallel with each other. A bead p extends around the curved portion n, angular portions o, and along each of the upwardly-extending portions m and joins the bead j of the body at the lower end of the end portion B. 60

The end portion C is substantially similar in appearance to the portion B, except that its angular portions o and curved portion n 65 extend in a direction opposite to those of the portion B.

The new design is distinctive in appearance, and the new shape when applied to a stereoscopic-picture holder renders the latter 70 symmetrical and pleasing to the eye.

What I claim is—

The design for a stereoscopic-picture holder substantially as herein shown and described.

In witness whereof I have hereunto signed 75 my name in the presence of two subscribing witnesses.

HENRY E. RICHMOND.

Witnesses:

GEORGE H. FRASER,
THOMAS F. WALLACE.
